ARTHUR A. ADAMS, OF BROOKLINE, MASSACHUSETTS, ASSIGNOR, BY MESNE ASSIGNMENTS, TO ATLANTIC NATIONAL BANK, OF PROVIDENCE, RHODE ISLAND, A CORPORATION OF RHODE ISLAND.

TARGET-PRACTICE APPARATUS.

1,086,882.

Specification of Letters Patent.

Patented Feb. 10, 1914.

Application filed January 26, 1907, Serial No. 354,263. Renewed July 5, 1913. Serial No. 777,492.

To all whom it may concern:

Be it known that I, ARTHUR A. ADAMS, a citizen of the United States, residing in Brookline, in the county of Norfolk and 5 State of Massachusetts, have invented an Improvement in Target-Practice Apparatus, of which the following description, in connection with the accompanying drawings, is a specification, like letters on the drawings 10 representing like parts.

My invention relates to target practice apparatus, consisting more particularly of simple and effective means for the practice of marksmanship and the production of a 15 record thereof.

My invention aims generally to improve existing types of target practice apparatus, wherein a miniature or other target is marked upon the simulation of firing, and 20 comprises novel features of construction and operation which will be best understood and appreciated by reference to the following description, when taken in connection with the accompanying drawings, of a single embodiment of my invention selected for purpose 25 of illustration, its scope being more particularly pointed out in the appended claims.

In the drawings: Figure 1, shows a marksman using a rifle provided with an attachment embodying one form of my invention, selected for purposes of illustration; Fig. 2, is an enlarged vertical section, with parts broken away, of the attachment shown in Fig. 1. Fig. 3, a plan thereof; Fig. 4, a vertical section, from the right, taken on the line 4—4. Fig. 2; Fig. 5, a similar section, from the right, taken on the line 5—5. Fig. 2; Fig. 6, a rear elevation, with parts broken away, of the needle adjusting devices, taken 35 from the left Fig. 1, and on the same scale as Fig. 2; Fig. 7, a horizontal section on the line 7—7. Fig. 6; Fig. 8, a front elevation of the attachment, the connection 39 being broken away for convenience of illustration; 40 Fig. 9, an elevation of the main target showing a modified arrangement of support therefor; and Fig. 10, a side elevation thereof.

In the particular embodiment of my invention herein selected for purposes of illustration, referring to the drawings, Fig. 1, I provide, as an example of an aiming device, a conventional type of rifle, in the present instance, the well known Krag-

Jorgensen rifle, though obviously, and it is to be understood, my invention is not restricted thereto, as it is not only equally applicable to rifles of other types or constructions but also to aiming devices other than rifles or the like. In the drawings, Fig. 1, the aiming device or rifle is provided with an attachment which is removably secured thereto and that may be readily attached to any fire arm. This attachment consists of a support, which may be of any desired form and construction to carry the recording devices hereinafter described, but I preferably provide a frame B of irregular shape comprising, the lower connecting arm 2, the rear vertical guide arms 3, and the upper arm 4, the head of the latter being secured to a sleeve 5 removably secured to the muzzle of the rifle, and the guide arms 3 being preferably integral with the foot 4' of the upper inclined arm 4. This sleeve 5, Figs. 2 and 3, is split longitudinally at its upper side and 75 provided with vertical flanges 8 having clamping screws 6 by which it is attached and clamped to the muzzle 7, of the rifle A. The said screws, 6, are separated longitudinally a sufficient distance to receive the rifle 80 sight, 9, between them, the latter being embraced at its sides, by said flanges 8, so that the sleeve 5 and the depending frame carried thereby may be rigidly secured to the rifle muzzle. This frame may be formed of any desired material, but is preferably very 85 light so that the weight of the attachment and its connections shall be inappreciable and thus avoid substantial increase in the customary weight of the rifle or other fire 90 arm that may be employed. To this end the arms 1, 2, 3 and 4, as well as other elements hereinafter described, are preferably 95 formed of light steel strip material suitably bent into desired shape.

While various changes may be made in the relation of the various associated elements, in the illustrated form of the invention the frame B, which, being attached to the muzzle of the rifle is obviously caused 100 to follow all the aiming thereof, is associated with and herein supports relatively movable recording or indicating devices. These herein comprise a reference object such as a sub or miniature target constituting a recording medium and a needle or 105

pointer constituting a recording member which, as the rifle is moved about the shoulder of the marksman and deflected relatively to the object aimed at, execute a following movement, the one relatively to the other in accordance with the deflections of the rifle. While the reverse might be the case, in the present instance the sub-target is held fixed upon the frame B while the point of the 5 needle, the latter fulcrumed upon the frame, is caused to move across the field of the miniature target in correspondence with the deflection of the line of sight relatively to the object aimed at. Such deflection of the 10 needle, or pointer relatively to the face of the miniature target are herein enforced and to a magnified extent by engagement with a directive element, the latter having a fixed relation relatively to the object aimed at, 15 so that movement of the aiming device causes such directive member to move the follower needle across the field of the target, and preferably to a degree greater than the actual deflection performed by the muzzle of the rifle. In the illustrated form of 20 the invention provision is made for the cooperation of the target, the follower needle and the directive member, all upon the frame B as follows: At its under side, the 25 sleeve 5 is provided with a lug or projection 10, Fig. 3, extending forward beyond the muzzle of the rifle to constitute suitable supporting means for a pivoted frame 11 Fig. 1, adapted to center and retain a miniature target or subtarget 12, in fixed position thereon, and to be oscillated on its pivot upon the simulation of firing. This frame 30 11 may also be of any suitable or desired shape or material, but is preferably made 35 as light as possible and to that end, and in the present embodiment of my invention, I provide a pair of thin steel strips 13, Figs. 2 and 8, each suitably fulcrumed at their sides and adjacent their upper ends to the 40 projection 10, as by a pin 14. The pivoted strips 13, are suitably connected at their upper ends to a curved cross or cam plate 15, the curved surface of which extends 45 across and directly in front of the muzzle 50 of the rifle in position to be actuated by suitable operating means at the time of firing. The operating means employed may be of any desired construction and operated by 55 mechanical, electrical, or other power. In the present instance, however, I have shown the bore of the rifle as provided with a light 60 plunger rod 16, its muzzle end contacting with the curved rear surface of the cross plate 15, so that a forward movement of the plunger will simultaneously actuate said 65 plate. The rear end of this plunger rod lies within the path of the forward end of the firing-pin of the gun (not shown), so that when the firing-pin is released by the trigger, at the instant of firing, said pin

and the plunger rod 16 are given a simultaneous forward movement. This movement oscillates said frame 11 and its supported subtarget, for the production of a record of the accuracy of aim as will presently be fully described. 70

The recording means, by which record of the accuracy of the aim is made, comprise the pivoted subtarget 12 and an indicating device or gyratory needle 18 pivotally mounted at its rear end on the guide arms 3, the latter, in the present instance, receiving between them an adjustable fulcrum support 17, Fig. 2, for the head of the needle. Any suitable fulcrum means may be 80 employed, but, in the present instance of my invention, I preferably provide the head of the needle 18 with a spherical bearing 19 which fits into a socket 20 on said support 17, the latter having a retaining screw 20*, 85 for securing the head within said socket and which may be turned to permit the removal of the needle. The arrangement is such that the needle has a universal gyrating or deflecting movement on its supported fulcrum 90 and while the latter is retained or held in any desired adjustment. To provide for adjustment of the support 17, any suitable means may be employed, but as here shown, I preferably provide its rear face with a 95 longitudinal rib 21, dove tailed in cross section, to fit in ways 22, formed in a vertically adjustable block 23, in turn slidably mounted between said arms 3. By this arrangement the support 17 may be moved laterally 100 so as to move the pivoted end of the needle to the right or left as in making allowance for wind, and to provide for fine adjustment said movement is effected by means of an adjusting screw 24, adapted to be turned by 105 hand.

The adjusting screw 31 is graduated with marks corresponding to the range marks of the rifle sights and the suitable index 31* is provided for indicating the position to 110 which said mark should severally be brought in adjusting the needle seat correspondingly. Similarly the lateral adjusting screw 24, similarly graduated, is provided with an index 24*. This screw, best shown in Figs. 115 7 and 8, in the present instance, is loosely mounted to rotate on two rearwardly extending ears 25 formed upon the block 23. The screw is provided with shoulders 26 to abut the right faces of said ears, Fig. 6, and 120 its left end receives a pin 27 and a washer 28, so that longitudinal movement is prevented. Intermediate its ends the screw is threaded through a rearwardly projecting lug 29 on the rib 21 of said support 17 so that upon 125 turning the screw in its supports the threaded portion causes said lug and hence said needle fulcrum support 17 to move to the right or left as desired. For vertical adjustment or elevation of this fulcrum sup- 130

port, the foot 4' of the arm 4, connecting the upper ends of the vertical arms 3, has a centrally and rearwardly projecting ear 30, Figs. 2 and 6, through which is threaded 5 an adjusting or thumb screw 31, having its foot rotatably secured to a similar ear 32 on the block 23. The sides of this block in the present instance, are provided with vertical rabbets or grooves 33, to receive inwardly projecting vertical ribs 34 on the vertical arms 3. By this arrangement, the block 23, thus confined to slide vertically on said arms 3, may be readily adjusted vertically by turning the thumb screw 31.

15 The needle 18 is pointed at its front end to pierce or puncture the sub or miniature target when the latter is swung toward it, the position to which said needle point is moved, by the oscillation of the needle, 20 relative to the subtarget, corresponding to the point to which the marksman directed his aim, as will now be made clear. That the needle may be moved relatively to the subtarget 12 and simultaneously by and 25 proportionate to the movements imparted to the rifle in aiming, suitable directive means are employed, in the present instance comprising an irregularly bent lever constituting the directive connection 35. To 30 place this in the most effective fixed relation to the frame and the needle this attachment preferably has universal connection with the frame or some part attached thereto, this being provided for in the present instance by the gimbal joint 36 secured in suitable manner to the upright arm 1. At 35 its opposite or rear end, this attachment has an upturned end 37 apertured at 38 to receive and embrace the needle 18 and which 40 through the operative connections thus afforded with the needle operates to produce deflections of the latter corresponding or proportionate to the deflections of the aiming device or rifle in sighting the same.

45 During practice the marksman holds the rifle in the usual fashion as indicated in Fig. 1, and takes aim through the rifle sight at the center or other desired point of the main target 42, placed at convenient distance from the marksman. As no other support or rest is provided other than that given by the marksman, I herein define my aiming device as a restless one. With the 50 gimbal joint 36, of the needle actuator or attachment 35 supported by the rifle and moving with the latter during the aiming movement, another fulcrum point is provided for said directive member at some other portion of its length by either fixedly holding it in position or offering some resistance to its movement. In the present instance, suitable means are provided for restraining the movement of the front end of the rod 39, here shown as effected by what 55 I term a drawing or a tensioning device and

comprising the cord 43 and its connections, hereinafter fully described, which operate to give said rod a directionally fixed relation to the object aimed at as the rifle is deflected. By this arrangement, the fulcrum or gimbal 70 36 being moved with the rifle the opposite end of the attachment is moved relatively to the frame and the needle and causes simultaneous deflection of the needle. The aperture, 38, of the attachment engages the 75 needle 18 at such distance from the fulcrum of the latter that the pointed end of the needle is moved or deflected a distance greater than the movement of the sight 9, so that the actual deflection of the needle 80 is a magnification of that of the line of sight. By this arrangement a much larger miniature target may be employed than one properly reduced in size to correspond to its distance from the point of sight as would be required were the angles of the deflection of the needle and rifle equal. As here shown, the actual deflection of the needle bears the same relation to the actual deflection of the rifle from the true line of 85 sight, *a*—*a*, Fig. 1, that the small miniature target bears to one properly reduced in size to the distance for its distance from the point of sight, so that the miniature target may be punctured or pricked by the needle 90 at a point thereon corresponding to the point on the main target to which aim was directed.

In order to provide suitable means for 95 moving the actuating end of the directive attachment, 35, toward or from the fulcrum of the latter, so as to vary the leverage of the needle for accurately adjusting the deflection, I have made the attachment extensible or telescopic. Any suitable means 100 may be employed for this purpose, but I preferably provide the lower arm of the attachment 35 with a horizontal portion 52, Fig. 2, which is formed, in any suitable manner, to provide a guideway 53, Fig. 5, 105 to receive the front end 54 of the needle engaging section of said attachment. In the present instance, these ways are formed by bending over the lateral edges of the metal strip of which the attachment 35 is 110 formed, said edges thus presenting flanges 55 to hold the parts of the attachment together, while permitting the needle engaging section to slide in said way 53.

The opposed ends of the two sections of 115 the attachment are provided with vertical ears 56, one of which has an adjusting screw 57, rotatably mounted thereon, the threaded portion of the screw engaging a threaded aperture in said ear, so that upon turning 120 the screw the needle engaging or apertured end of the attachment may be moved back and forth. While in the present embodiment of my invention the printed subtarget pictures are of uniform size, this arrange- 125 130

ment provides efficient means for adjusting the needle deflections for different sizes of target pictures so that the needle deflections will correspond proportionately to that of the rifle, and be adapted to the subtarget used. It will furthermore be understood that by varying or adjusting the leverage of the needle the deflections of the latter may be made much greater than a deflection of the needle that normally corresponds to the deflection of the line of sight, thus providing what may be termed auxiliary magnification means for magnifying the deflection of the needle and which may be utilized for magnifying or eliminating errors in aiming and recording the same.

The rod 39 forming the front end of the directive member and which is pivotally connected to the frame B through the said gimbal joint 36 is provided with suitable means to hold its front end in relatively stationary position during the process of aiming the rifle and already referred to as tensioning or resistance means comprising the cord 45 and its connections. As here shown, the attachment arm 35 is counterbalanced by the rod 39 and a disk 40, Figs. 2 and 3, said disk being connected through said tensioning means to an extraneous support here connected with or adjacent the main target 42 or other object at which aim is to be directed.

My invention contemplates the provision of suitable means for producing or permitting movement of the main target during aiming and simulated firing so as to increase the difficulty of aiming and thus to reproduce actual conditions of firing. As here shown, this is secured by mounting it on an oscillating frame 42^a (Figs. 9 and 10) here shown as mounted to swing pendulum like from a pivot 42^b on any suitable support, such as the wall of a room. When a movable main target is employed, I preferably tension the cord by means of a light coil spring 44^x connecting the end of the cord 45 that passes over the pulley 41 with the target frame 42^a, said spring however yielding to permit extending the length of range within certain limits or it may be replaced by a longer and lighter one.

In using my aiming device in combination with a movable main target, I have found that any movement of the latter and its connected pulley to the right or left vertically or lengthwise, produces a corresponding movement of the follower independent of or additional to that produced by the movement of the aiming device, so that the marksman not only has to aim at a desired point on a target but has to follow the same in its movements. The movements of the main target and aiming device by their combined action on the follower, cause the resulting deflection of the follower to fol-

low that of the line of sight, that is of the aiming device, so that a marksman in using my apparatus has the desired practice and becomes proficient in aiming at movable targets or other objects as well as those that are stationary. By providing the pulley and cord stretching means the marksman may move toward and from the main target for varying the length of range.

It will be observed that the relation of the parts is such that the aim-fixing spot on the bull's-eye of the main target 42 is at a distance above the bull's-eye on the sub or miniature target approximately equal to the distance of the line of sight above the action of the marker 18. It will also be seen that the screw 24 and the connected parts provide a means for adjusting the relation between the line of sight, the marker, the bull's-eye and the aim-fixing spot so that the line of action of the marker may be offset from a vertical line through the bull's-eye when the line of sight is directed on the aim-fixing spot.

The tensioning device employed may be of any desired construction but I prefer that here shown, Fig. 1, comprising the substantially inelastic cord or string 43, running over the pulley 41. The lower end of this cord is provided with suitable means for stretching the cord or putting it under tension for example a spring, or as here shown, one or more weights 44, the rear end of said cord being connected at 45 to the ends of three similar cords or strands 46 which at their rear ends are adjustably connected to said disk 40. In the present instance, the rear ends of the cords are respectively connected to the outer ends of three spring controlled levers 47, Figs. 2 and 4, pivoted as by pins 48, on radially and forwardly projecting ears 49, provided at three equally distant points on the circumferential portion of said disk. The outer ends of the levers are apertured to receive the ends of the cords which are passed through the apertures and knotted or otherwise secured to said levers. At their inner ends these levers are provided with adjusting screws 50, Fig. 2, the ends of which engage the front face of the disk, against which they are normally retained by coil springs 51, arranged between said pins 48 and the outer arms of said lever. By turning these adjusting screws the disk and its rod may be deflected as desired correspondingly to deflect the needle to bring its point to desired normal position, or to desired variation therefrom. I thus provide a very convenient means for adjusting the rod 39 to parallelism with the true line of sight or a line passing through the rifle sights and center of the target 42, *i.e.* the line, *a—a*, Fig. 1, or to any desired angle therewith. The three point connection of the cords 46, also

prevents any undesirable flexing thereof, or any of them, at a point adjacent the rifle and constitute what may be termed a truss frame, for normally retaining the disk perpendicular to the true line of sight. (a—a, Fig. 1.) The arrangement described is such that the cord 43, the rod 39 and through intermediate connections, the fulcrum of the needle 18 are normally alined when the marksman aims, so as to bring the rifle sights on the true line of sight a—a Fig. 1. This is attained by placing the pulley 41, in such position that the normal position of the axis of the cord 43, the centers of the gimbal 36 and spherical needle head 19 shall be in a straight line and parallel with the true line of sight. With the top of the pulley and said centers in line it is apparent that any movement of the center of the gimbal 36 produced by like movement of its supporting frame 1 or the rifle muzzle will also cause a greater and like movement of the upturned end 37 of the needle actuator and this through the aperture 38 correspondingly deflects the needle and in the same direction.

The directive member 35 constitutes in effect a follower directionally fixed relatively to the main target and caused to execute a following movement relatively to parts upon the frame B. By providing the separate and ultimate following medium or needle relative following movement, which ensues between the directive element and the frame, is converted into a following movement between the needle and target of exaggerated though proportionate value.

The cards or other blanks on which the targets are printed are of uniform dimensions and the target impressions are symmetrically placed thereon, so that the distance from the edges of the cards to the concentric rings and bull's-eye or center are the same on each, each subtarget being in all respects an exact duplicate or copy of another.

The miniature target is carried or received by a subtarget holder 58, secured at the lower ends of the strips 13, Fig. 8. As here shown, this holder comprises a metal plate 59 provided at its rear or target-supporting face with a pad or blank 60 of leather or other yielding material for forming a suitable backing for the target. This arrangement permits the needle to perforate through the subtarget into the backing so that a clean cut hole is made in the subtarget. The holder 58 is provided with subtarget retaining devices on three sides, by which the said subtarget is located and centered thereon so that each subtarget will occupy the same position. The fourth side of the holder being left open permits the subtarget to be readily inserted or removed.

As here shown, these retaining devices are

formed by providing the top and bottom of the holder with reversely bent flanges 61, the top and bottom edges of the plate 59 being turned over for this purpose. At its left side the holder has a laterally bent edge or flange 62 against which a side of the subtarget abuts and which serves as a gage for the proper positioning thereof. The holder is normally retained in a forward position away from the needle point by a coil spring 63, connecting it with the upright 1, and acting to swing the holder and its pivoted support toward the latter.

That actual conditions of firing or range practice may be readily reproduced, it is desirable to provide suitable means for accustoming the marksman to the shock of recoil. This condition is readily fulfilled by withdrawing the plunger rod and firing blank cartridges, the compression and discharge of the exploded gases, at the instant of firing, acting with sufficient force on the cam plate to swing the target toward the needle to produce the desired record. The momentum of the target holder produced either by the plunger or by a blank cartridge, is sufficient to swing the target against the needle point to effect the necessary record, the spring 63 yielding to permit the rearward movement of the subtarget to its normal position and thus also clearing it from the needle. By this means, the subtarget is moved to produce an instantaneous record.

While I have herein shown the apparatus as employed with a main or distant target, the aim to which is recorded upon a separate or sub-target, my invention is not limited to the use of separate and distinct target elements as contrasted with the same target element to serve both as the object aimed at and the recording medium.

By my invention, I have provided a very simple and efficient device of low cost adapted to be attached to any kind of a gun or other aiming device and that because of its small weight not only does not interfere with the accuracy of the aim but is adapted to be readily carried about and set up in any suitable place for practice.

My invention obviously, is not limited to the specific embodiment herein selected for purposes of illustration only, nor to the specific details of construction and arrangement, it being understood that the same may be varied or modified within wide limits without departing from the spirit and scope thereof.

I claim:

1. An aiming device provided with mechanism including a recording member and a recording medium supported by and movable only with the movement of said aiming device and connections between the aiming device, recording member and recording medium for effecting a record of the aim.

130

2. A target practice apparatus comprising an aiming device independent of supporting devices other than that given by the marksman in handling the same and means comprising a target, a follower, and a device for relatively moving said target and follower for effecting a record of the aim, said means being supported by and movable with said aiming device.
- 10 3. An aiming device having means mounted thereon and movable therewith comprising target and follower devices for effecting a record of the aim.
- 15 4. An aiming device and an aim recording attachment mounted thereon movable therewith and comprising target means and a movable indicating member for effecting a record of the aim on said target means.
- 20 5. A target practice apparatus comprising an aiming device having means mounted thereon movable therewith and including a target, a movable indicating member, and connected mechanism, for effecting a record of the aim.
- 25 6. A target practice apparatus comprising in combination, a main target, an aiming device, of an attachment carried by said device having means including a recording member and a recording medium for effecting a record of the aim thereof.
- 30 7. In an apparatus of the type described, a restless aiming device having a follower to follow the aim of said aiming device, a sub-target, and connected mechanism for effecting a record of the aim.
- 35 8. In an apparatus of the type described, an aiming device having aim recording devices mounted thereon and movable therewith, comprising a movable indicating member and a target to be marked by said indicating member for effecting a record of the aim.
- 40 9. An aiming device having means supported thereby and moving therewith for effecting a record of the aim and comprising an indicating member and a sub-target adapted for relative movement therewith to effect said record.
- 45 10. A target practice apparatus, provided with a freely movable aiming device for aiming at a distant target or like object and following means mounted on said device and to follow the aim thereof with relation to a reference object by a movement separate from and additional to that of the aiming device.
- 50 11. A target practice apparatus, provided with an aiming device for aiming at a target or like object, following means mounted on said aiming device to follow the aim thereof with relation to a sub-target, said sub-target being also carried by and movable with said aiming device, and connected mechanism for effecting a record of the aim.
- 55 12. A target practice apparatus having an unsupported aiming device free for movement when in the hands of the marksman, an indicator mounted on said aiming device, means to cause said indicator to follow the movements of said aiming device by a movement separate from and additional to that of the aiming device, and connected mechanism for effecting a record of the aim.
- 60 13. A target practice apparatus having an aiming device and means mounted on said aiming device and movable therewith for effecting a record of the aim, comprising a follower connected therewith to follow the aiming movements of the aiming device, and means to vary the ratio between the movement of said follower and said aiming device.
- 65 14. A target practice apparatus adapted to be held by the marksman, comprising an aiming device for aiming at a distant target, following means for indicating the accuracy of the aim, and means for adjusting the apparatus to correctly indicate the aim for ranges of different length.
- 70 15. A target practice apparatus provided with an aiming device for aiming at a target and means supported by and movable with the aiming device for effecting a record of the accuracy of the aim thereof, comprising a recording member and a sub-target, one of which is adapted to follow the movement of the aiming device during aiming.
- 75 16. A target practice apparatus provided with an aiming device for aiming at a target, and means supported by said device and movable therewith for effecting a record of the accuracy of the aim thereof, comprising a recording member and a sub-target, mechanism connected with one of them for causing it to follow the movement of said aiming device during aiming, and means to produce relative movement between said sub-target and said recording member for producing said record.
- 80 17. A target practice apparatus provided with an aiming device for aiming at a target, and means supported by said device and movable therewith for effecting a record of the accuracy of the aim thereof, comprising a recording member and a sub-target, and means for relatively moving the same to cause one of them to follow the aim of the aiming device and for producing said record.
- 85 18. A target practice apparatus having an aiming device, a gyroscopic needle mounted on said device, a target, and means for causing relative movement of the same and said needle at the time of simulated firing, for effecting a record of the accuracy of aim.
- 90 19. A target practice apparatus having an aiming device, a gyroscopic needle mounted on said device, a target, means for causing relative movement of the same and said needle at the time of simulated firing, for effecting a record of the accuracy of aim and

- adjusting means connected with said needle for varying the gyratory movement of said needle.
20. A target practice apparatus having an aiming device, following means carried by said device to follow the deflections of said aiming device during aiming relatively to a reference object, and means for varying the ratio between the deflection of said aiming device and said following means. 70
21. A target practice apparatus having an aiming device for aiming at a distant target, means carried thereby and comprising a recording member to follow the movements of said aiming device during aiming, a sub-target, means for varying the ratio between the movements of said aiming device and said recording means, and means relatively to move said sub-target and recording members, for effecting a record of the aim. 75
22. A target practice apparatus provided with an aiming device, a main target at which the aiming device is to be aimed, and aim recording means comprising a recording member and a sub-target, mounted on said aiming device and movable therewith to record the aim thereof, at the time of simulated firing, said aim recording means having a connection with a point extraneous to 80 said aiming device for causing one of its elements to follow the aim of the aiming device during aiming.
23. A target-practice apparatus having an aiming device, a target at which aim may be taken, and means, carried by and movable with said aiming device, comprising a recording medium, an indicating medium, and connected mechanism, for effecting a record of the aim. 85
24. A target-practice having an aiming device, a target at which aim may be taken, and means carried by the aiming device comprising a sub-target and connected mechanism actuated through the barrel of the aiming device for effecting a record of the aim 90 at simulated firing. 100
25. A target-practice apparatus having an aiming device, a fulcrumed attachment therefor and a tensioning device connected 105 with the latter and with an extraneous support located in the direction in which aim is to be taken, to cause the attachment to move in correspondence with the deflections of the aiming device. 110
26. In a target-practice apparatus, an aiming device having a follower, a fulcrum therefor carried by said aiming device, a target at which aim is to be directed and a device connected with a point adjacent to 115 said target for effecting relative movement between said follower and said aiming device upon aiming the latter, to cause the follower to follow the movements of said aiming device. 120
27. In a target practice apparatus, an 125 aiming device provided with a fulcrumed follower and flexible directive means having operative connection at one end therewith and normally extending in the same direction as the line along which aim is to be directed and at the opposite end connected with an extraneous support. 130
28. In a target practice apparatus, an aiming device provided with a fulcrumed follower, a flexible cord having operative connection at one end with said follower, a guiding device for the opposite end of said cord mounted upon a support in the vertical plane containing said cord, and a tensioning device therefor. 135
29. In a target practice apparatus, an aiming device provided with a fulcrumed follower, a flexible cord having operative connection at one end with said follower, a guiding device for the opposite end of said 140 cord mounted upon a support in the vertical plane containing said cord, and a tensioning device therefor, said means comprising one or more weights secured to the end of said cord, the arrangement being such as to permit the length of cord between said aiming device and said guiding device to be varied 145 thereby to extend the range. 150
30. In a target-practice apparatus, an aiming device provided with a fulcrumed follower, an inelastic cord or string connected at one end to direct said follower and normally extending in the same general direction as the line along which aim is to be taken, an extraneous support for the opposite end of said cord, and means for tensioning said cord to impose a slight resistance to the free movement of the connected end of 155 said follower to cause it to follow the movement of the aiming device during the aiming movement thereof. 160
31. In a target-practice apparatus, an aiming device provided with a fulcrumed follower, an inelastic cord or string connected at one end to direct said follower and normally extending in the same general direction as the line along which aim is to be taken, an extraneous support for the opposite end of said cord, and means for tensioning said cord to impose a slight resistance to 165 the free movement of the connected end of said follower to cause it to follow the movement of the aiming device during the aiming movement thereof, said support comprising a pulley over which said cord runs 170 and said tensioning means, a weight at the end of said cord. 175
32. An aiming device adapted to be aimed at a target and a follower carried thereby having a flexible connection with a support 180 in the direction of said target and to co-operate with the aiming movement of said aiming device for causing said follower to follow the aim thereof. 185
33. A target practice apparatus having an 190

- aiming device, a target mounted thereon to move therewith and upon which record of the aim is to be made, a follower for following relatively to the target the deflection of 5 the aiming device and means for moving the target upon simulation of firing to cause it to engage said follower in its following position for effecting a record of the accuracy of the aim.
- 10 34. A target practice apparatus, comprising in combination, an aiming device provided with a follower, a target at which aim is to be directed, and a connection between the target or a point fixed with reference thereto and said follower, to cause the latter to follow the aiming movement of the aiming device.
- 15 35. A target practice apparatus, comprising in combination, an aiming device provided with a follower, a target at which aim is to be directed, a connection between the target and said follower to cause the latter to follow the aiming movements of the aiming device, and adjusting means for varying the normal position of the follower.
- 20 36. A target practice apparatus, comprising in combination, an aiming device provided with a follower, a target at which aim is to be directed, a connection between the target and said follower to cause the latter to follow the aiming movements of the aiming device, and means for varying the following movements of said follower.
- 25 37. A target practice apparatus, comprising in combination, an aiming device provided with a follower, a movable target at which the aim of the aiming device is to be directed and a connection between the said movable target and follower to cause the latter to follow the movements of said target and said aiming device.
- 30 38. A target practice apparatus, comprising in combination, an aiming device provided with a follower pivotally mounted thereon and means for retarding the free movement of said follower to cause it to follow the aiming movements of the aiming device, said means including a cord connected with said follower and an extraneous support.
- 35 39. A target practice apparatus, comprising in combination, an aiming device provided with a follower pivotally mounted thereon and means for retarding the free movement of said follower to cause it to follow the aiming movements of the aiming device, said means comprising a cord connected at one end to an extraneous support and provided with diverging strands or extensions at its opposite end each connected with said follower.
- 40 40. A target practice apparatus, comprising in combination, an aiming device provided with a follower pivotally mounted thereon and means for retarding the free movement of said follower to cause it to follow the aiming movements of the aiming device, said means comprising a cord connected at one end to an extraneous support and provided with diverging strands or extensions at its opposite end each connected with said follower.
- 45 41. A target practice apparatus, comprising in combination, an aiming device provided with a follower pivotally mounted thereon and means for retarding the free movement of said follower to cause it to follow the aiming movements of the aiming device, said means comprising a plate, and plurality of cords connected with peripheral portions of said plate and having their opposite ends connected with an extraneous support located in the direction of aim.
- 50 42. A target practice apparatus, comprising in combination, an aiming device provided with a follower pivotally mounted thereon and means for retarding the free movement of said follower to cause it to follow the aiming movements of the aiming device, said means comprising a plate, and plurality of cords connected with peripheral portions of said plate and having their opposite ends connected with an extraneous support located in the direction of aim, and means for varying the effective length of one or more of said cords.
- 55 43. An aiming device having a follower for following the aiming movements thereof and a movable support independent of rest or suspensory means for one end of said follower.
- 60 44. In a target practice apparatus, an aiming device having an attachment provided with following means to indicate or record accuracy of the aim thereof, said means comprising a connection between the same and a support adjacent the target or other object at which aim is to be directed, and having provision to permit extension of the range.
- 65 45. In a target practice apparatus, an aiming device having an attachment adapted to be moved therewith during the aiming movements thereof and provided with means for indicating or recording the accuracy of the aim and to permit the marksman to move toward or from the target, or other object at which aim is to be directed, for varying the length of the range.
- 70 46. In a target practice apparatus, an attachment for an aiming device, comprising a sleeve 5, having a rearwardly inclined arm 4, vertical arms 3 depending from the latter; a front arm 1 connected with said sleeve, and a lower connecting arm 2.
- 75 47. In a target practice apparatus, an aiming device, a sleeve 5 adapted to be secured thereto and provided with a forwardly pro-

jecting lug 10, and a target carrying frame 11 pivotally mounted thereon.

48. In a target practice apparatus, an aiming device, an attachment therefor provided with a pivoted target holding frame, and a spring for normally maintaining the head of said frame in juxtaposition to the muzzle of said aiming device.

49. In a target practice apparatus, an attachment adapted to be secured to an aiming device having a directive member 39, a disk 40 secured thereon and strands 46 connected with said disk.

50. In a target practice apparatus, an attachment for an aiming device provided with a directive member 39, a disk 40 secured thereon having a plurality of ears 49, and strands 46 provided with means for connecting them with said ears, said means comprising a plurality of levers 47 adjustably pivoted thereto.

51. A target practice apparatus having means for indicating or recording the aim thereof, comprising a fulcrumed directive member and a flexible truss connection connected therewith and with a point adjacent the target or other object to which aim is to be directed.

52. In an attachment for an aiming device, a fulcrumed directive member, a disk 40 longitudinally adjustable thereon and cords 46 secured at one end to said disk and at points equally distant from one another and from said member, the opposite ends of which are connected with a support mounted adjacent the target or other object at which aim is to be directed.

53. In an attachment for an aiming device adapted to be mounted thereon and movable therewith, a gyratory needle 18, a fulcrumed member 35 for causing the same to follow the aiming movements of said rifle and provided with means for varying the leverage upon said needle and thereby the deflection of the same relative to said aiming device.

54. In an attachment for an aiming device, a depending frame provided with vertical arms 3, a block 23 mounted for vertical adjustment between said arms, a needle seat 17 mounted for lateral adjustment in said block 23, a needle 18 fulcrumed in said seat, and means for moving said block or seat to effect adjustment of the needle 18.

55. In a target practice apparatus a follower having connection with a point adjacent the target or other object at which aim is to be directed and means for magnifying the deflections of the same relative to the deflections of said aiming device.

56. In a target practice apparatus, an aiming device, a follower, a target or like object at which the aim of the aiming device is to be directed, a pulley or the like

supported adjacent said target, a flexible strand or cord connected with said follower and running over said pulley, and having a weight attached to its fall end.

57. In a target practice apparatus, an aiming device, a movable follower for following the aiming movement thereof, a connection between the same and an extraneous support, and a weight connected with the supported end of said connection to effect tension thereof.

58. In a target practice apparatus, an aiming device, a follower for following the aiming movement of the said device provided with tensioning means including a weight for giving normal direction thereto.

59. In a target practice apparatus, an aiming device, a follower, means engaging the same and means for drawing or directing the same toward a point fixed with reference to a target or other reference object at which aim is to be directed.

60. In a target practice apparatus, an aiming device, a recording device, a recording medium and a flexible connection between the latter and a point fixed with reference to a target or like object, to cause relative movement between the recording device and recording medium in accordance with the movements of the aiming device.

61. In a target practice apparatus, an aiming device having means for indicating or recording the accuracy of the aim thereof, comprising two elements movable relatively to each other and carried by and movable with the aiming device, and means for holding one of said elements directionally fixed while permitting the other to follow the deflections of the aiming device with reference to a target or other reference object and to indicate or record the aim of the aiming device.

62. In a target practice apparatus, an aiming device, and aim recording means, comprising a pivoted target carrier adapted to be oscillated upon discharge of said device for effecting a record of the aim.

63. A target practice apparatus having an aiming device, a main target at which aim may be taken, relatively movable recording devices carried upon and movable with said aiming device, and means engaging the same having a fixed relation relatively to the main target, said recording devices providing for a record of the deflection of the aiming device relatively to the main target to a magnified degree.

64. An aiming device provided with mechanism including a recording member, and a recording medium supported by and movable only with the movement of said aiming device and connections between the aiming device, recording member and recording medium for effecting a record of the aim.

65. A target practice apparatus comprising an aiming device independent of supporting devices other than that afforded by the marksman in handling the same, and means comprising a target, follower and a device for relatively moving said target and follower for effecting a record of the aim, said means being supported by and movable only with the movement of said aiming device.
66. An aiming device having means mounted thereon and movable with the movement of the aiming device, said means comprising target and follower devices for effecting a record of the aim.
67. The combination with an aiming device of an aim recording attachment comprising a plunger rod adapted to be inserted in the bore of the rifle and propelled therein by the firing mechanism thereof, and a target on which the aim is recorded by the forward movement of the plunger rod, and windage adjusting means whereby the record aim may be adjustably varied from the true aim taken at the bull's-eye.
68. The combination with an aiming de-
- vice of an aim recording attachment therefor comprising a plunger member adapted to be inserted in the bore of the fire arm and propelled therein by the firing mechanism thereof, a target on which aim is recorded by movement of the plunger, a marker, means for showing an aim fixing spot at a distance above the target approximately equal to the distance of the line of sight above the line of action of the marker, and means for adjusting the relation between at least two of said factors, to wit, the line of sight, the marker, the bull's-eye and the aim fixing spot to offset the line of action of the marker from a vertical line through the bull's-eye when the line of sight is directed on the aim fixing spot.
- In testimony whereof, I have signed my name to this specification, in the presence of two subscribing witnesses.

ARTHUR A. ADAMS.
